UNITED STATES PATENT OFFICE.

FRANK D. SHEPHERD, OF SALT LAKE CITY, UTAH.

TWO-CYCLE MULTICYLINDER INTERNAL-COMBUSTION ENGINE.

Application filed July 22, 1921. Serial No. 486,681.

To all whom it may concern:

Be it known that I, FRANK D. SHEPHERD, residing at Salt Lake City, county of Salt Lake, and State of Utah, a citizen of the 5 United States, have invented certain new and useful Improvements in Two-Cycle Multicylinder Internal-Combustion Engines, of which the following is a specification.

10 My invention relates to internal combustion engines and in what I regard as the best and completest embodiment of my invention relates to two-cycle multicylinder engines, some of my objects being maximum 15 utilization of fuel energy, certainty of a full charge of mixture for supply to the cylinder for the power stroke, thorough scavenging of the burnt gases and hence assurance of the purity of the charge as far as contamination by residual gases in the cylinder is concerned, compactness of structure, and withal extreme simplicity of parts. Other 20 objects attained by and advantages of my invention will appear from the detail description hereinafter given or will be understood or appreciated by those skilled in the art. My invention accordingly consists in an 25 internal combustion engine having the construction described by or embraced within the scope or meaning of the appended claim.

In the annexed drawings:

Fig. 1 is a view partly in side elevation and partly in vertical section of a four cylinder two-cycle engine embodying my invention;

Fig. 2 is a section on the line 2—2 of Fig. 1;

Fig. 3 is a detail view in elevation from the inner side of the plate which contains or 40 forms part of the transfer passages between the cylinders of a connected pair;

Fig. 4 is a detail view in section showing a different form of inlet controlling or suction valve from that shown in Figs. 1 and 2;

Fig. 5 is a detail view in section of an embodiment of my invention in which no transfer controlling valve is employed.

The embodiment of my invention shown in the drawings is an internal combustion 50 engine for motor vehicles, but it is to be understood that I do not restrict myself only to such an engine, and it is also to be understood that while the engine shown in the drawings is of the water-cooled type, I

do not confine myself to that type of engines as engines embodying my invention may be of the air-cooled type; and while I show ignition means using spark plugs, it is to be understood that my invention may be embodied in engines having other gas ignition means. It is also to be understood that I do not restrict myself to a four cylinder engine as the number may be more or less, but the number should be either two or multiples of two in order to embody my invention in what I now consider its most advantageous form.

The four cylinders designated, respectively, 10, 11, 12, and 13, are cast en bloc with a single detachable head, 14, for the 55 four, a gas tight joint, of course, being made between the head and the cylinders, and all of the cylinders open at the bottom into the crank case, 15, within which rotate the cranks of the crank shaft, 16, but as will 60 appear hereinafter by my invention the gas is not taken from the crank case and hence the subdivision of the crank case into separate units, which is necessary in multi-cylinder two-cycle engines that take gas from the 65 crank case, is avoided and so the objectionable length of a multi-cylinder engine due to such subdivision or partitioning is 70 avoided. Moreover, by the non-use of the crank case as the source from which the gas 75 is taken, I overcome one of the objections to the use of two-cycle engines for motor vehicles which is that idling speeds are impossible because of inadequate compression 80 of the gas at idling speeds.

The internal construction of each of the 85 four cylinders is exactly the same. Each has a bore in two sections, one section being of smaller diameter than the other, the two 90 sections being coaxial, and each section being fitted with its own piston, the small piston, 17, being the power piston, and the large piston, 18, the fuel charging piston, and the cylinders are arranged in pairs so 95 connected by ports or passages that a charge 100 of gas is passed from the cylinder of the charging piston, 18, to the combustion chamber of the power piston, 17, of the adjacent cylinder. The pistons of a thus connected pair of cylinders are connected with 105 cranks of the crank shaft, 16, 180° degrees apart. The cranks of the four pistons, however, are 90° apart. Thus the arrangement

is such that during the power stroke of a power piston, 17, a charge of gas will be drawn through an inlet port, 19, into the cylinder of the charging piston, 18, of that power piston, 17, and simultaneously a charge previously drawn into the cylinder of the adjacent charging piston, 18, will be forced into the connected cylinder of the adjoining power piston, 17.

10 The inlet port, 19, is at the end of the cylinder of the charging piston adjoining the cylinder of the power piston is in axial alinement therewith and hence is only covered by the charging cylinder piston 15 when the latter completes its charging stroke and therefore is open throughout practically the whole of the suction stroke of such charging piston. I therefore employ a valve in the passage, 20, which leads from an inlet manifold, 21, to which is connected a carburetor, 22, of suitable construction, which valve automatically opens on the suction stroke of the charging cylinder piston and automatically closes on the transfer 25 stroke of that piston, the result of that arrangement being that the charging piston on its suction stroke does not work against or for the production of a high vacuum in order to cause the flow of a charge of mixture into its cylinder preliminary to transfer to the associated power piston cylinder, and hence energy that would be consumed in the production of such a high vacuum is conserved. Again, as the flow of the mixture into the charging piston begins immediately after the start of the charging piston in the direction to produce the suction flow of the mixture and such flow continues until the limit of travel of the piston 30 in that direction is reached, there is ample opportunity for a full supply of fuel mixture to the charging cylinder before the transfer movement of its piston begins.

40 The suction valve arrangement is preferably that shown in Figs. 1 and 2 the valve, 23, being of the poppet-piston type, its piston, 24, fitting the interior of a housing, 25, and being engaged by one end of a coil spring, 26, that acts normally to move the valve to its seat, 27, and yieldingly holds it to its seat. Of course, during the transfer travel of the charging piston a pressure is thereby produced on the valve which tightly holds it to its seat so that none of the 45 gas of the charge being transferred to a power cylinder can pass back into the inlet manifold. The other end of the valve seating spring, 26, bears against a disk, 28, in the housing, 25, which disk is engaged by 50 the inner end of a screw, 29, that passes through a threaded hole in the block or cap, 30, which closes the upper end of the housing, the adjusting screw being provided so 55 that there may be necessary adjustment of the pressure of the spring to assure the

movements of the valve, 23, with such nicety as the speed requirements of the engine may call for. To give the underside of the valve, 23, a greater area than that of the upper side of the piston, 24, the piston is perforated by holes, 31, sufficient in number and area to give the required differential area. Of course, the housing or container, 25, is air or gas tight so that gas entering the same through holes, 31, cannot escape, nor can air 75 enter the container from the outside.

As may best be seen by reference to Figs. 1 and 3, the transfer passages which connect the charging and power cylinders of adjacent sets extend diagonally across one another, each passage communicating at one end with the charge outlet port, 32, from the charging cylinder and at the other end with the inlet port, 34, of the associated power cylinder. One of these passages comprises a groove or channel, 35, in the outer side of the cylinder wall which is covered or closed on the outer side by the flat surface of a plate, 36, which is bolted to the cylinder side, while the other passage consists of a channel, 37, formed in the plate, 36, this arrangement resulting in a compact structure free from objectionable lateral protrusion or projection from or at the side of the engine. The housing, 25, and the walls of the passage, 20, are preferably cast integrally with the plate, 36, so that all these parts are in one member which makes for simplicity and inexpensiveness of construction and is further important in eliminating the presence of joints at points where imperfect joints would result in the escape of fuel mixture. It is in this connection that the employment of the piston type valve shown in Figs. 1 and 2 is important because the interior of the housing, 25, has a diameter sufficiently large, compared with the diameter of the valve, 23, to permit the assembly and removal of the valve through the container or housing. Thus the only joints 100 are between the side of the plate, 36, and the cylinder and with the inlet manifold, 21.

The inlet port, 34, in the embodiment of my invention shown in Figs. 1 and 2, leads to the top of the power cylinder through a passage, 38, in the cylinder head, 14, communication between the inlet port, 34, and the power cylinder being controlled by a poppet valve, 39, which normally is yieldingly moved to its seat, 40, by a coil spring, 41, in a housing, 42, projecting from the top of the head, 14, the valve having a stem, 43, which reaches into such housing and which has a head, 44, against which the spring presses. The valve, 39, however is wholly automatic in its opening and closing movements, it opening when during the power stroke of a power piston, the pressure in the cylinder of such piston is reduced by reason of the opening of the exhaust port, 45,

below the pressure in the inlet port, 34, and closing when the compression stroke of such power piston takes place. The tension of the spring, 41, is adjustable by similar means to what I show in the case of the suction valve spring, 26, that is to say, the spring, 41, bears against a disk, 46, which is engaged by the inner end of an adjusting screw, 47, passing through a threaded opening in the head or cap, 48, of the container or housing, 42.

The exhaust ports, 45, lead to a manifold, 49, and the exhaust port, 45, in the case of each power cylinder is opened and closed by the travel of the power piston of that cylinder, the opening of the port, of course, beginning just before the completion of the power stroke and the port accordingly being at the opposite end of the power cylinder furthest from the inlet port, 34. As a result of the relative arrangement of inlet and exhaust ports and by reason of the employment of the transfer controlling valve, 39, it is assured that thorough scavenging of the burnt gases shall take place without any substantial quantity thereof being left to mix with the incoming charge of fresh mixture. During the power stroke of a power piston the valve, 39, will be held to its seat thus holding back in the transfer passage and the inlet port, 34, leading to such valve the mixture under pressure in such passage and inlet port because of the transfer travel of the charging piston so that when the poppet valve, 39, eventually opens in consequence of the uncovering of the exhaust port, 45, by the power piston, the fresh mixture will pop or rush with considerable velocity into the upper end of the power cylinder and with but little diminished velocity will flow down into the latter and thus most advantageously act upon the burnt gases to drive them out of the exhaust port. On the return compression stroke of the power piston the exhaust port will be cut off or covered sufficiently soon to prevent any substantial escape of the fresh mixture through the exhaust port. At the instant the power piston completes its power stroke the poppet valve, 39, as shown in Fig. 2, has not fully closed the inlet port, 34, but at once upon the beginning of the compression stroke of such power piston and due to the action of the spring, 41, the valve, 39, seats and thus back flow of the fresh mixture that is entering the power cylinder is prevented.

Each power piston, 17, has suitable packing rings, 50, and lubrication holding grooves, 51, the latter being situated so that at no time do they enter the adjacent charging piston cylinders, the result being that the entire portion of the power piston that enters the charging piston cylinder is smooth and uninterrupted, but to provide lubrication for that portion of the power piston I

provide lubricant holding grooves, 52, in the walls of the power piston cylinder at the ends adjacent the charging piston cylinder. These grooves as well as those in the piston form seals which prevent the passage of gases between the power and charging piston cylinders.

To facilitate assembling, the end of the power cylinder where it opens into the charging piston cylinder is chamfered at 53, 75 so that the piston, 17, with its packing rings, 50, loosely applied thereto may be inserted into its cylinder through the charging cylinder, and such rings in a loose expanded state engaging the chamfered or beveled surface 80 will be squeezed or cammed into position and thus readily enter the cylinder along with the piston, 17.

Each charging piston, 18, is of such length and the extent of its travel is such that at 85 all times its sides bear against the internal walls of the cylinder and thus the inevitable side thrust from the connecting rod connection between the crank and the piston is prevented from wearing the cylinder walls so as 90 to render the same concave or barrel shape with the result that greater lateral strain would be thrown on the power piston and like wear on its cylinder occur, and opportunity afforded for gas communication between the charging piston cylinder and the crank case and between the two cylinders. I find that to secure this result the charging piston should have a length equal to at least substantially half its stroke. Each charging 100 piston, 18, has suitable packing rings, 54, near each end, and lubricant holding grooves, 55, near each end.

The various ports over which the pistons move are preferably of grid form, as shown 105 in the drawings, to provide narrow slots instead of an opening of extended area and thereby danger of the piston rings catching on the edges of the ports is prevented.

It will be seen that a pair of cylinders 110 and the two pistons of each constitute two sets, as what I have termed a cylinder section is in reality a cylinder. Thus for each set there is a power piston and a connected charging piston and a cylinder for each of 115 such pistons, and in the embodiment of my invention illustrated in the drawings there are really four sets of power and charging pistons and cylinders therefor.

When I employ four cylinders and arrange them in pairs so that the pistons of cooperating pairs are connected with the crank shaft 180° apart, and that considering all four pistons the cranks are successively 90° apart, I fire the cylinders in the order 120 1, 4, 2 and 3, because that prevents any objectionable unbalanced strains from the piston thrust on the crank shaft. The result is due to the fact that with such an order of firing when, for example, cylinder 10 has 125

fired and is exhausting, the piston of cylinder 13 is on the power stroke, and therefore exerting force in the same direction on the crank shaft, the two points of application 5 of the two forces in the same direction being thus symmetrically situated with reference to the shaft bearings, and in like manner the two intermediate cylinders, when their pistons are under power, are simultaneously 10 exerting power in the same direction on the crank shaft and at symmetrical distances from the shaft bearings.

As the cranks are 90° apart and an explosion occurs at every fourth revolution of 15 the crank shaft, the power is applied to the shaft in a smooth steady flow, and, hence, vibration of the shaft is eliminated. Thus as a result of this crank arrangement and the firing order described, the engine is of high 20 efficiency and free from objectionable strains.

The top of the cylinder or combustion chamber is formed by surfaces that are compound curves, the general shape of the chamber being that of a frustum of a cone with 25 the spark plug, 140, at the apex, the surfaces next the spark plug being convex, and those in the lower part being concave, a chamber being thus provided free from angular 30 pockets or corners, and the surfaces against 35 which the explosion reacts having such relation to the power end of the piston as to compel the direct application of the force of the expanding gas to the piston, and by reason of the gradually enlarging space from the spark plug to the piston effecting 40 a progressive ignition of the gas from the spark plug to the piston.

As shown in Fig. 4 a suction valve, 57, may be employed different in construction 45 from the suction valve shown in Figs. 1 and 2. As said valve 57 has a downwardly projecting stem, 58, and a spring container, 59, this necessitates a lateral projection, 60, from the plate, 61, which contains or forms 50 part of the transfer openings for connection with the inlet manifold, so that it is not so desirable a construction as that shown in Figs. 1 and 2, because it is not so compact for it throws the manifold and carburetor 55 a considerable distance to one side of the engine.

In Fig. 5, an embodiment of my invention is shown which dispenses with the transfer 60 controlling valve, 39, by making the power piston, 62, control the inlet port, 63, to the power piston cylinder, 64, the inlet port, 63, being thus located at the bottom of the power cylinder so as to be uncovered only when the power stroke is finished. Inasmuch as in this case the inlet port, 63, and the exhaust port, (not shown in Fig. 5), are open at the same time, the power receiving 65 end of the piston, 62, has a rib, 65, that deflects the incoming fresh mixture upward in-

to the cylinder and prevents its escape 65 through the exhaust port. The suction valve arrangement shown in Fig. 5 is the same as that shown in Figs. 1 and 2, consisting of the valve, 66, with a piston, 67, in a container or housing, 68, in which the piston 70 slides, the housing, 68, being cast integral with the plate, 69, which contains or provides the transfer passages, 70.

It will be observed that though valves are employed by me, no cams are required to 75 lift them from their seats and yet their operation is automatic, such operation being dependent upon the pressure in the cylinders produced by the travel of the pistons therein, the elimination of lifting cams thus resulting in simplification of the engine and being otherwise advantageous. The valves, it will be seen, perform the functions of a check valve in that they permit flow of fluid 80 in one direction while preventing its flow 85 in the opposite direction, although unlike the ordinary check valve, seating is not dependent upon pressure in the direction that would tend to seat them because it is important, as by means such as the seating 90 springs, to cause the seating of the valves before any back flow of gas could take place so as to assure that no gas or mixture will be lost through the valves when the pistons move in the direction to effect either the 95 transfer of the mixture from a charging cylinder to a power cylinder or to effect the compression of a charge newly introduced into a power cylinder.

It will be noted that the housing or container for the valve seating spring and the valve guiding piston or stem has no communication with the external air and hence even though by leakage past the piston or 100 stem or passage through holes in the piston 105 as in the valve shown in Figs. 2 and 5, gas might enter the container or housing, it could not escape therefrom and hence no loss of gas or pressure could occur.

It is to be understood that my invention 110 may be embodied in engines with the various parts or members constructed and arranged differently from what I illustrate in the drawings and may be described with some detail, and the scope of my invention is to be determined not by what I have shown and described but by what is defined by or comprehended within the language or meaning of the following claim.

What I claim is:

An internal-combustion engine having two sets of cylinders, each set comprising two cylinders and a piston for each cylinder, one piston being a power piston and the other a charging piston, the cylinder of the power piston having inlet and exhaust ports and the cylinder of the charging piston having inlet and outlet ports, an inlet to the 115 120 125

charging piston cylinder, a check valve controlling flow through said inlet, conduits connecting the outlet port of each charging cylinder of one set with the inlet of each power cylinder of the other set, a plate separate from the cylinders containing one of said conduits, the other conduit being

formed by a channel in the cylinder wall and an adjacent side of said plate, and housings for said valves integral with said plate, ¹⁰

In testimony whereof I hereunto affix my signature.

FRANK D. SHEPHERD.
